UNITED STATES PATENT OFFICE.

WILLIAM W. BAGLEY, OF NEW YORK, N. Y.

TOWEL-CABINET.

1,305,048.

Specification of Letters Patent. Patented May 27, 1919.

Application filed May 18, 1918. Serial No. 235,399.

To all whom it may concern:

Be it known that I, WILLIAM W. BAGLEY, a citizen of the United States, and a resident of the city of New York, borough of 5 Manhattan, in the county and State of New York, have invented a new and Improved Towel-Cabinet, of which the following is a full, clear, and exact description.

My invention relates to towel cabinets for 10 individual towel service, and has reference more particularly to a cabinet which will afford storage room for a plurality of packages of clean towels so secured to the cabinet that they cannot be removed therefrom 15 except for placing the packages into serviceable position.

An object of the invention is to provide a cabinet of the class described having accommodation for a plurality of packages 20 of towels which can be attached to or removed therefrom only in package form by the delivery man.

Another object of the invention is to provide a package towel carrier which has 25 means whereby the towels cannot be removed by the delivery man, although he can attach or detach the package from the towel cabinet.

A still further object of the invention is 30 to provide a towel carrier which will discharge only one towel at a time.

With the above and other objects in view, the nature of which will more fully appear as the description proceeds, the invention 35 consists in the novel construction, combination and arrangement of parts as herein fully described, illustrated and claimed.

In the accompanying drawings, forming 40 part of the application, similar characters of reference indicate corresponding parts in all the views.

Figure 1 is an elevation of one form of towel cabinet embodying my invention, a portion of the basket for the soiled towels 45 being broken out to show the details of construction;

Fig. 2 is a vertical section on line 2—2, Fig. 1;

Figs. 3, 4 and 5 are sectional views 50 through the end of the arm which supports the package of clean towels and which illustrate the successive positions of the means

which prevent the removal of more than one towel at a time;

Fig. 6 is a similar section showing a 55 modified form of the means controlling the removal of one towel at a time;

Fig. 7 is a section through the double lock provided at the end of the flexible member of the towel carrier; 60

Fig. 8 is a cross section through the lock on line 8—8, Fig. 7, showing the same in operation with the key controlling one of the locking means;

Fig. 9 is a similar section showing it with 65 a key controlling the operation of the other locking means;

Fig. 10 is an elevation of the arm of the towel carrier, the means for locking the arm in the support being shown in section, also 70 the lock for locking the towels on the arm being partly broken out to show the details of construction;

Fig. 11 is an elevation of the arm support; and 75

Fig. 12 is an elevation of the lock on the arm.

In individual towel cabinets it is of great importance to limit the handling of loose towels by the delivery man, for such handling requires counting, which is expensive in view of the amount of time required. Furthermore, with such handling of towels there is a loss of towels and, therefore, the method is not economical. To overcome 80 such handling of the towels I provide towel carriers for each package so that a package of towels after being used individually cannot be taken off the carrier except by an authorized person. In other words, the delivery man only controls the packages of either clean or soiled towels, and has no access to the carrier to remove or place the towels thereupon, this being done at the 85 laundry.

Referring to the drawings, the cabinet presents a basket 13 for soiled towels above which a suitable support 14 is provided into which an arm 15 of any of the towel carriers may be locked so that the arm will project from the wall of the cabinet to which the support 14 is secured. The support 14 has a spring-actuated plunger 16 normally tending to engage a bore 17 in the 90 95 100

end of the arm which enters the support. The support has also a pair of lugs 18 with which the ear 19 of the plunger is adapted to align when the plunger is in normal position. To these lugs 18 the ear of the plunger may be locked so that the arm 15 cannot be removed by the delivery man without the authorization of the proprietor of the place where the cabinet is located.

- 10 The arm 15 also receives from the end which engages the support a collar 20 which has a lock bolt 21 operable by a key so that said collar 20 may be locked to the bolt in proximity to the support, as shown 15 best in Fig. 10, the arm 15 having a recess or opening 22 for the bolt 21. This collar 20 when removed permits the fitting of the clean towels on to the arm through the end which is to be engaged by the support 14.
- 20 The towels are prevented from slipping off the other end of the arm by a spring-actuated catch 23. When the desired number of towels is fitted on the arm 15 the collar 20 is locked thereto and the clean towels, therefore, are retained on the arm by the collar 20 and the catch 23.

The catch 23 has a shoulder 24 which is slightly wider than a ring 25 of an individual towel 26. This shoulder is adapted 30 to be flush with the surface of the arm when the catch is maintained in the normal position by the spring 27. It will be seen that the catch can only be moved toward the proximate end against the resistance of the 35 spring. The tendency to move the catch in the opposite direction is resisted by the engagement of the toe 28 of the catch with the bottom of the arm. The shoulder 24 being only slightly wider than a ring 25, another 40 towel in proximity to the one engaged by the shoulder will be prevented from slipping off by the rotation of the catch (see Fig. 4), for it will shove the proximate towel ring away from the one being carried over the 45 catch 23.

The end of the arm at the catch has also a loop 29 from which a flexible member 30, such as a chain for example, is suspended. The end of the chain can be slipped into the 50 casing of a lock 31 wherein a bolt 32 is provided for engaging the link entering the casing, a suitable key 33 being provided therefor. The same key preferably controls the lock for the plate 21 in the collar 20. In 55 consequence, all the towels that have been used or which are soiled will be found on the flexible member 30, from which they cannot be removed unless the last link of the chain is unlocked from the bolt 32.

60 The same lock casing 31 carries another bolt 34 which is operated by a different key 35, both entering the same key opening in the lock casing, and which is adapted to lock the bail 36 to the casing 31. 65 This key 35 is in the possession of the de-

livery man for locking and unlocking the towel carriers from the bottom of the basket 13 whereat a plurality of eyes 37 are provided so that a corresponding number of such carriers may be locked thereto.

70 One of the arms of the carrier is secured to the support 14 in a manner previously described, the towels being allowed to hang from the support as shown in Figs. 1 and 2. Preferably a screening board 38 is hinged to the cabinet so that only a portion of the front towel is exposed above the screen. The screen is preferably hinged on one side, or removable, if so desired, to facilitate the placing or removing of the arm of a carrier 75 from a support. The other arms with their towels thereon are stored in a suitable receptacle 39 which may be provided above the basket as shown or to one side. The bottom of the receptacle has a slot 40 to one 80 side so that the flexible members 30 of the carriers may not interfere with the closing of the door 41 of the receptacle nor with the towels which are disposed in serviceable 85 position in the support 14.

90 Access to this cabinet is controlled by the proprietor of the place where the cabinet is located, and when all the towels on the arm 15 and the support 14 have been used up, he removes the arm 15 from the support, for he controls the plunger 16, and drops the same into the bottom of the basket. He then takes another bundle out of the receptacle 39 and places the arm 15 of same into engagement with the support 14. The screen 95 38 is first swung to one side to facilitate the placing of the arm into the support and also for bringing the chain 30 outside of the screen. It will be noted that at no time is there more than one bundle of towels accessible to the users.

100 When the man delivers the packages of towels, he removes those packages the arms of which are in the basket 13 by disengaging the bails 36 from the eyes, the flexible member still remaining in engagement with its lock so that the delivery man cannot take off any of the towels on the flexible members. For the packages of towels which he removes he substitutes other packages by 105 simply locking the bails of those locking members to the eyes in place of those removed, the packages being stored away in the receptacle 39 by the proprietor of the place.

110 By having a locked storage compartment at the cabinet, a plurality of bundles may be kept in reserve, thereby permitting the customer to have a sufficient number of towels on hand without giving the public access to more than one package at a time. This storage of packages also reduces the delivery expense of the supply man to a great extent, which is one of the most expensive items of the individual towel cabinet system.

The catch 23' shown in Fig. 6 has the shoulder 24' sufficiently wide to accommodate two rings 25 of the towels thereon, and when two rings like that are in engagement with the shoulder 24' the rotation of same is prevented as will be seen from Fig. 6. In consequence a person could not pull off two towels at the same time. One of the towels would have to be moved off the shoulder before the one in front of same could be moved off the arm supporting the clean towels.

From the above description it will be seen that the arm 15 is the clean towel package carrier, while the flexible member 30 is the soiled towel carrier; that each of those carriers has independent locking means, the arm having the collar 20 and the flexible member having the locked bolt 32. It is self-evident that in place of using a twin lock as shown, two independent locks can be provided at the end of the flexible member, one for locking the soiled towels thereon and the other for locking the end of the flexible member to the bottom of the basket.

It is self-evident that in place of using the basket 13 the ends of the flexible members 30 may be secured directly to the back wall of the cabinet and the soiled towels allowed to hang from the flexible member. In place of the collar 20 on the arm 15 a padlock can be substituted, the tail of which would pass directly through the opening in the arm.

I claim:

1. In combination, a basket for soiled towels, means for securing a plurality of towel carriers to the basket, a support for presenting in serviceable position a package of clean towels of one of the secured towel carriers, and a receptacle for storing the packages of clean towels of the other carriers secured to the basket.

2. In combination, a basket for soiled towels, means for securing a plurality of towel carriers to the basket, a support for presenting in serviceable position a package of clean towels of any of the carriers secured to the basket, and a receptacle for storing the packages of clean towels of the other carriers secured to the basket, said receptacle having means for the carriers so that the same may protrude from the receptacle to the basket to which the carriers are locked, any of said packages of clean towels of any of the carriers being removable from the receptacle to be placed into serviceable position into the support while all of the carriers remain secured to the basket.

3. In combination, a basket for soiled towels, means for locking a plurality of towel carriers to the basket, a support for presenting in serviceable position a package of clean towels of any of the carriers secured to the basket, and a receptacle for

storing the packages of clean towels of the other carriers locked to the basket, any of said packages of clean towels of any of the carriers being placeable into serviceable position into the support while all of the carriers remain locked to the basket.

4. In combination, a basket for soiled towels, a plurality of towel carriers each having an arm for accommodating a package of clean towels and a flexible member 75 for accommodating the soiled towels, means for locking the ends of the arm and flexible member so as to prevent the removal of the towels therefrom, means for locking the flexible members to the basket, a support 80 for receiving an arm to present any package of clean towels so locked in serviceable position, and a receptacle for the towels on the arms, said receptacle having a slot for the flexible members of the towel carriers so that 85 the same may extend from the receptacle to the basket to which they are locked.

5. In combination, a basket for soiled towels, towel carriers each comprising an arm for receiving packages of clean towels 90 and a flexible member forming an extension of the arm for receiving the soiled towels coming from the arm, locking means at the end of the arm and at the end of the flexible member for locking the towels thereon, 95 means in the basket whereby a plurality of the locked ends of the flexible member may be detachably secured, a support for the arm of any towel carrier so locked to present a package of clean towels in serviceable position above the basket, and a receptacle for the arms with the remaining packages of clean towels thereon, the ends of the flexible members of which are secured in the basket, said receptacle having a slot to one side for 100 the flexible member to pass out from the receptacle to the basket.

6. A towel carrier for towel cabinets comprising a rigid member on to which towels may be threaded, a flexible member connected to one end of the rigid member, a spring-actuated catch associated with said rigid member in proximity to the flexible member, said catch presenting a portion 110 projecting above the rigid member and a shoulder normally flush with the surface of the rigid member, said shoulder being adapted to receive but one towel, which towel when pulled toward the portion of the catch above the rigid member will spring 115 the catch and allow the towel to slip on to the flexible member, a locking collar adapted to be secured to said rigid member in proximity to the end remote from the flexible member, and a lock for the end of the flexible member for retaining the towels thereon. 120

7. A towel carrier for towel cabinets comprising a rigid member provided with a loop and a flexible member connected to said loop, a catch, means pivotally connecting 125 130

the catch to the rigid member in proximity to the loop, said catch having a shoulder, a spring for maintaining said shoulder flush with the surface of the rigid member, said catch having a toe normally preventing the spring from depressing the shoulder below the surface of the rigid member.

8. A towel carrier for towel cabinets comprising a rigid member, a flexible member connected thereto, a spring-actuated catch on said rigid member in proximity to the flexible member preventing the feed of more than one towel at a time from said rigid member to the flexible member, and a twin lock associated with the end of the flexible member, one of said locks being adapted to lock the towels on the flexible member and the other to lock the flexible member to any desired support.

Copies of this patent may be obtained for five cents each, by addressing the "Commissioner of Patents, Washington, D. C."

9. In combination, a basket for soiled towels, a plurality of towel carriers each having an arm for accommodating a package of clean towels and a flexible member for accommodating the soiled towels, a twin lock associated with the end of each of the flexible members of the carrier, one of the twin locks on the flexible member serving for securing the flexible member to the basket, a support for receiving an arm of a carrier to present a package of clean towels in serviceable position, and a receptacle for the packages of towels on the arms, said receptacle having means so that the flexible members may pass out of the receptacle to the basket to which the flexible members are locked.

WILLIAM W. BAGLEY.
